UNITED STATES PATENT OFFICE.

RAYMOND W. DULL, OF LA GRANGE, ILLINOIS, ASSIGNOR TO LINK BELT COMPANY,
OF CHICAGO, ILLINOIS, A CORPORATION OF ILLINOIS.

LINK FOR CHAIN BELTS.

1,394,980.

Specification of Letters Patent.

Patented Oct. 25, 1921.

Application filed March 22, 1920. Serial No. 367,654.

To all whom it may concern:

Be it known that I, RAYMOND W. DULL, a citizen of the United States, residing at La Grange, in the county of Cook and State 5 of Illinois, have invented a certain new and useful Improvement in Links for Chain Belts, of which the following is a specification.

My invention relates to integral links for 10 chain belts formed from sheet metal of substantially uniform thickness.

Some of the objects of my invention are to provide a wide, supporting base for the hook; substantially tubular, closely fitting, 15 interlocking pintle and hook ends; and to form said parts so as to reduce the waste of material in stamping the link from the blank to a minimum.

Other objects and advantages not herein 20 necessary to be mentioned will be found characteristic of my invention.

It will be understood that I do not wish to be limited to the particular proportions 25 of parts here shown as they may be greatly varied without departing from the spirit of my invention. The hook end is shown in the preferred form but it can be made in any one of a variety of ways. The pintle end may be made as suggested by its parts 30 being bent in either direction.

The invention illustrated in the accompanying drawings, wherein:

Figure 1 is a view of a blank from which such link may be formed;

Fig. 2 is a plan view of a finished link; and

Fig. 3 is a side elevation of a section of a chain composed of such links.

Like parts are indicated by the same letters in all the figures.

A is the blank, the body of which is substantially rectangular in form with the projection B at one end. C indicates the inner part of the link which is stamped out along 45 the lines indicated by C¹ to form the hook. The finished link comprises the side bars D, D, the end bars E, F, and the two portions C, B. The end bar E is bent to one side of the body of the link so as to form 50 a portion of the hook and the hook portion C is then bent from the inner edge of the side bar E down and around, upwardly and inwardly toward the outer edge of the side bar so as to form a hook. The 55 pintle end is formed by bending the side

bars at a distance from the end of the hole left by stamping out the part C and then bending the end bar F around and bending the part B around between the side bars D, D, until its end edge is in substantial contact with the other edge of the side bar F. These bends can take place in either direction, but I prefer to have them so that the approaching or opposed edges of the parts which form the two tubular ends lie on the 60 same side of the body of the link.

It will of course be observed that some of the features of my invention can be obtained without using the others.

It will be understood of course that the 70 size and proportions of the several parts could be greatly varied without departing from the spirit of my invention and I do not wish therefore to be limited to the precise relations shown in the drawings. 75

Claims:

1. An integral single thickness sheet metal chain link comprising two side and two end bars and two substantially tubular ends, the pintle end having an external diameter 80 approximately the same as the internal diameter of the hook, and the hook end consisting of an end bar bent away from the body of the link and a second part cut from the body of the link departing from the inner edge of such end bar and bent around until close to and in opposition to the outer edge of said end bar. 85

2. An integral single thickness sheet metal chain link comprising two side and two end bars and two substantially tubular ends, the pintle end having an external diameter 90 approximately the same as the internal diameter of the hook, and the hook end consisting of an end bar bent away from the body of the link and a second part cut from the body of the link departing from the inner edge of such end bar and bent around until close to and in opposition to the outer edge of said end bar, the opposed edges of the parts which form the hook and the pintle ends being on the same side of the link. 95

3. An integral single thickness sheet metal chain link comprising two side and two end bars and two substantially tubular ends, the pintle end having an external diameter 105 approximately the same as the internal diameter of the hook, and the hook end consisting of an end bar bent away from the 110

body of the link and a second part cut from the body of the link departing from the inner edge of such end bar and bent around until close to and in opposition to the outer edge of said end bar, the pintle and hook ends projecting on both sides of the body of the link.

4. An integral single thickness sheet metal chain link comprising two side and two end bars and two substantially tubular ends, the pintle end having an external diameter approximately the same as the internal diameter of the hook, and the hook end consisting of an end bar bent away from the body of the link and a second part cut from the body of the link departing from the inner edge of such end bar and bent around until close to and in opposition to the outer edge of said end bar, the opposed edges of the parts which form the hook and the pintle ends being on the same side of the link, the pintle and hook ends projecting on both sides of the body of the link.

5. An integral single thickness sheet metal chain link comprising two side and two end bars and two substantially tubular ends, the pintle end having an external diameter approximately the same as the internal diameter of the hook, and the hook end consisting of an end bar bent away from the body of the link and a second part cut from the body of the link departing from the inner edge of such end bar and bent around until close to and in opposition to the outer edge of said end bar, the opposed edges of the parts which form the pintle being so far bent as to overlap.

6. An integral single thickness sheet metal chain link comprising two side and two end bars and two substantially tubular ends, the pintle end having an external diameter approximately the same as the internal diameter of the hook, and the hook end consisting of an end bar bent away from the body of the link and a second part cut from the body of the link departing from the inner edge of such end bar and bent around until close to and in opposition to the outer edge of said end bar, the opposed edges of the parts which form the hook being separated by a distance equal substantially to the thickness of the sheet metal, the opposed edges of the parts which form the pintle being so far bent as to overlap.

7. An integral single thickness sheet metal chain link adapted to be formed from an imperforate link blank, comprising two side and two end bars, two substantially tubular ends, the pintle end having an external diameter approximately the same as the internal diameter of the hook, and the hook end consisting of an end bar and a tongue of metal cut from the body of the link to form the open central portion of the link.

8. An integral single thickness sheet metal

chain link adapted to be formed from an imperforate link blank, comprising two side and two end bars, two substantially tubular ends, the pintle end having an external diameter approximately the same as the internal diameter of the hook, and the hook end consisting of an end bar and a tongue of metal cut from the body of the link to form the open central portion of the link, departing from the inner edge of such end bar and bent around until close to and in opposition to the outer edge of such end bar.

9. An integral single thickness sheet metal chain link comprising two side and two end bars and two substantially tubular ends, the pintle end having an external diameter approximately the same as the internal diameter of the hook, the pintle end consisting of an end bar and an outer projection therefrom, the two being bent to form a cylinder, the hook end consisting of an end bar bent away from the body of the link and a second part cut out from the body of the link and bent around until close to and in opposition to the outer edge of such bar.

10. An integral single thickness sheet metal chain link comprising two side and two end bars and two substantially tubular ends, the pintle end having an external diameter approximately the same as the internal diameter of the hook, the link adapted to be struck from an imperforate link blank, the pintle end being formed in part from an outward projection from one end of said blank.

11. An integral single thickness sheet metal chain link comprising two side and two end bars and two substantially tubular ends, the pintle end having an external diameter approximately the same as the internal diameter of the hook, the link adapted to be struck from an imperforate link blank, the pintle end being formed in part from an outward projection from one end of said blank, the hook end consisting of an end bar, and a tongue cut from the interior of the link, the link body being pierced only by the opening formed by the removal of said interior tongue.

12. An integral single thickness sheet metal chain link comprising two side and two end bars and two substantially tubular ends, the pintle end having an external diameter approximately the same as the internal diameter of the hook, the link adapted to be struck from an imperforate link blank, the pintle end being formed in part from an outward projection from one end of said blank, the hook end consisting of an end bar, and a tongue cut from the interior of the link.

In testimony whereof, I affix my signature this 16th day of March, 1920.

RAYMOND W. DULL,
